UNITED STATES PATENT OFFICE.

ULRICH SPRINCHORN, OF JAMESTOWN, NEW YORK.

CURTAIN-SUPPORT.

1,205,805.

Specification of Letters Patent. Patented Nov. 21, 1916.

Application filed February 4, 1916. Serial No. 76,196.

To all whom it may concern:

Be it known that I, ULRICH SPRINCHORN, a subject of the King of Sweden, residing at Jamestown, in the county of Chautauqua 5 and State of New York, have invented certain new and useful Improvements in Curtain-Supports, of which the following is a specification.

This invention relates to improvements in 10 curtain rods and supports, the main object in view being to provide a simple article from which to suspend draperies preferably, in combination with the customary window-shade.

15 The essence of the invention lies in the provision with a curtain rod formed with support engaging extremities of such a character as to enable interchange or reversal of the position of the rod when desired, of 20 a support or bracket to hold the rod in off-standing position with respect to the window-frame.

A further object is to form the support 25 so as to permit of the bodily adjustment of the rod with respect to the window-frame with which it coöperates.

For a full understanding of the present invention, reference is to be had to the following detail description, and the accompanying drawings, wherein:

Figure 1 is a perspective view showing the present invention in operative position upon a window-frame. Fig. 2 is a fragmentary view showing one end of the device 35 in elevation. Fig. 3 is an end elevation. Fig. 4 is a perspective view of the bracket support for the rod; and Fig. 5 is a detail view showing more clearly the rod extremity.

40 Throughout the following detail description, and on the several figures of the drawings, similar parts are referred to by like reference characters.

Specifically describing the invention, the 45 numeral 1 designates a window-frame and 2 the usual roller shade supported upon the shade rod 3 which in turn is supported by the window brackets 4 attached to the frame 1 by suitable means such as the screws 5. It will be observed more particularly from 50 Fig. 4 of the drawing that the bracket 4 consists of a metallic plate, the upper portion of the body of which is bent outwardly to form an offstanding arm or ledge 6. The 55 ledge 6 is relatively wide for reasons here-

inafter more particularly pointed out. The metal of the offstanding arm 6 is cut at its opposite corners to form stop members 7, said members 7 being slightly bent out of the plane of the upper edge of the arm. At 60 one side, furthermore, the plate 4 is preferably provided with a spur 8 which is bent at right angles to the body and is adapted to be driven into the window-frame when attaching the bracket in position, for the 65 purpose of preventing the bracket from rotating about its supporting screw 5 as a pivot. The lower edge of the bracket plate is formed with the shade supporting hook 9 in which the rod 3 hereinbefore mentioned 70 is adapted to be disposed. The bracket therefore provides a combination support for the shade rod as well as for the curtain rod 10 now to be described.

The rod 10, preferably comprises telescoping sections so as to enable it to be used with windows of different widths and, furthermore, the rod is formed of sheet metal having its longitudinal edges bent to provide inner flanges 11, the flanges of one 80 section coöperating with the other section to secure the telescoping action. As shown in the drawing, the rod is preferably bent at its end portions at substantially right angles and each end of the rod is bifurcated 85 or slotted as indicated at 12, thereby forming corresponding hooks 13.

In the use of the curtain rod 10, it will be understood that the ends are engaged with the offstanding arms 6 of the plates 90 4, with the upper hooks 13 extending over the edge of said arms. The lower hooks 13 as shown in Fig. 3 coöperate with the plate or with the arms, more strictly speaking, against which said hooks have a bearing for 95 supporting the rod in offstanding position with respect to the window-frame. The advantage of the formation of the rod, as above described lies in its adaptability to windows of different widths owing to the 100 sectional construction as well as its sliding engagement with the bracket supports, whereby the rod may be bodily adjusted with respect to the window-frame. The accidental disengagement of the ends of the 105 rod from the bracket supports is prevented by the stop members 7 as will be quite obvious. Furthermore, if for any reason the rod becomes bent downwardly, due for instance to sustaining the weight of heavy 110

draperies, the said rod may be reversed and the engaging of the hooked extremities interchanged. With this particular arrangement, one does not have to be careful as to the insertion of the rod sections into the heading of the curtains or other draperies to be suspended therefrom as it is immaterial which side is uppermost. Obviously, this facilitates the operation of hanging curtains and a most effective support is provided therefor. Both the rod and its support may be easily and cheaply manufactured.

Having thus described the invention, what is claimed as new is:

1. A curtain support comprising a rod having each end thereof slotted in a direction longitudinally of the rod to form upper and lower corresponding bracket engaging elements at each of said ends, and a bracket adapted to be received in said slot for supporting engagement by either of the engaging elements, the other of said elements

abutting against the bracket to hold the rod in offstanding position.

2. A curtain support comprising a rod having a T-shaped slot at each end, said slot forming at one side a bracket engaging hook and at its other side an abutment member for holding the rod in offstanding position, and a bracket adapted to be received in said slot engageable by the hook and abutment aforesaid.

3. A curtain support comprising a rod having a bracket engaging extremity, a bracket consisting of a plate having an outwardly bent portion forming a horizontal ledge with which the rod extremity is slidably engaged, whereby to permit of bodily adjustment of the rod laterally of the bracket, and stop means formed upon said bracket to limit sliding adjustment of the rod.

In testimony whereof I affix my signature.

ULRICH SPRINCHORN.
